UNITED STATES PATENT OFFICE.

CARL WEEKS, OF DES MOINES, IOWA.

DESIGN FOR A TALCUM-POWDER BOX.

Application filed June 5, 1922. Serial No. 2,535. Term of patent 3½ years.

To all whom it may concern:

Be it known that I, CARL WEEKS, a citizen of the United States, and a resident of Des Moines, in the county of Polk and State of Iowa, have invented a certain new, original, and ornamental Design for a Talcum-Powder Box, of which the following is a specification, reference being had to the accompanying drawing, forming part thereof.

Figure 1 is a plan view of my talcum powder box.

Figure 2 shows a front elevation of the same; and

Figure 3 shows a side elevation.

I claim:

The ornamental design for a talcum powder box, as shown.

Des Moines, Iowa, May 15, 1922.

CARL WEEKS.
